Primary Examiner — Sharon S Oum(74) *Attorney, Agent, or Firm* — McGarry Bair PC**CLAIM**

The ornamental design for a ceiling fan light kit and motor housing assembly, as shown and described.

DESCRIPTION

FIG. 1 is a top perspective view of a ceiling fan light kit and motor housing assembly, showing my new design in the environment of a ceiling fan;

FIG. 2 is a bottom perspective view thereof;

FIG. 3 is a top view thereof;

FIG. 4 is a bottom view thereof;

FIG. 5 is a front view thereof;

FIG. 6 is a left side view thereof;

FIG. 7 is a rear view thereof; and,

FIG. 8 is a right side thereof.

Portions of the ceiling fan light kit and motor housing and the ceiling fan environment shown in broken lines form no part of the claimed design.
